ATTORNEY

UNITED STATES PATENT OFFICE.

JOSEPH RITTER, OF MILWAUKEE, WISCONSIN.

CANDLE-HOLDER.

1,229,140.

Specification of Letters Patent. Patented June 5, 1917.

Application filed January 19, 1917. Serial No. 143,360.

To all whom it may concern:

Be it known that I, JOSEPH RITTER, a citizen of the United States, residing at Milwaukee, in the county of Milwaukee and 5 State of Wisconsin, have invented new and useful Improvements in Candle-Holders, of which the following is a specification.

This invention is an improved candle holder or candle stick, the object of the invention being to provide an improved device 10 of this character which is cheap and simple in construction and which is adapted to receive and hold candles of various sizes, diameters and shapes, and is not liable to be 15 clogged by dripping candle grease.

The invention consists in the construction, combination and arrangement of devices hereinafter described and claimed.

In the accompanying drawings:—

20 Figure 1 is a plan of a candle holder, in the form of a candle stick, constructed and arranged in accordance with my invention.

Fig. 2 is a vertical transverse sectional view of the same.

25 In the embodiment of the invention here shown a saucer or base 1 is provided which has a dome 2 provided with a central opening 3 the wall of the said opening extending downwardly and being provided with an inwardly extending annular flange 4 at its lower side.

I also provide springs 5 of which any suitable number may be employed, two being here shown. Each spring comprises a 35 base portion or member 6, upwardly and inwardly inclined portions 7 at the ends of the base member, and downwardly extending free end and counterengaging portions 8. Each end of the spring is connected to 40 the inclined portion 7 by a curved portion 9 and each inclined portion 7 is connected to the depending free end portion 8 by a curved portion 10 so that each inclined portion 7 is adapted for radial and vertical 45 angular movement with respect to the base portion and each free end portion 8 is also adapted for radial and vertical angular movement with respect to the inclined portion. The free end portions 8 are arranged 50 in opposed and in parallel relation and are adapted to engage a candle placed between them to support and hold the candle,

springs by reason of their construction, herein before described, permitting the depending free end portions to move toward and 55 from each other and hence adapting the device to grasp and hold a candle of any diameter, size or shape. Said end portions are curved transversely to guide and fit the 60 candle.

As here shown the base members or portions 6 of the springs or candle grasping fingers are arranged in crossed relation and secured between a pair of disks 11, 12, by rivets or other suitable devices 13. The said 65 disks are also secured by rivets 14 to a disk 15 which is arranged and held in the opening or recess 3 and bears on the flange 4.

I would have it understood that any suitable supporting element may be employed 70 in connection with my candle holder as well as the base or saucer here shown, so that the candle holder may be used in connection with sconces or other like devices as desired. The candle holder may be made of any suitable 75 material.

While I have herein shown and described a preferred form of my invention I would have it understood that changes may be made in the form, proportion and construction of the several parts, without departing 80 from the spirit of my invention and within the scope of the appended claim.

Having thus described my invention, what I claim is:—

In a candle holder, a plurality of radially arranged spring candle grasping fingers each having a base member, an inclined portion, a curved portion connecting the base and inclined portions and also having a downwardly extending free end and candle engaging portion and a curved portion connecting the inclined portion and free end and candle engaging portion, the said free end portions of the springs being opposed 90 and arranged in parallel relation, in combination with a supporting element having a recess, disks between which the base members of the springs are secured and an element extending downwardly from the lower 95 disk and arranged in said opening or recess. 100

In testimony whereof I affix my signature.

JOSEPH RITTER.
